UNITED STATES PATENT OFFICE

2,498,119

PEAKING TRANSFORMER

Lester D. Drugmand, Greenfield, and Edward M. Hampe, Richfield, Wis., assignors to Cutler-Hammer, Inc., Milwaukee, Wis., a corporation of Delaware

Application August 5, 1948, Serial No. 42,568

3 Claims. (Cl. 171—119)

1

The invention relates to improvements in transformers and particularly so-called peaking transformers for supplying ignition voltage to gaseous discharge tubes and the like.

An object of the invention is to provide an improved transformer in which the magnetic flux interlinked with the secondary winding increases rapidly with and substantially proportionally to a magnetomotive force produced by a primary current, but only while such magnetomotive force is below a given maximum, such flux remaining substantially constant for any further increase of said magnetomotive force.

Another object is to provide an improved transformer which, when energized by a sinusoidal primary current, induces a secondary voltage which both rises to and falls from its maximum amplitude abruptly, said maximum persisting only for an instant.

Another object is to provide such a transformer which is small for its capacity and inexpensive to manufacture.

Another object is to provide for such a transformer an improved magnetic coupling between the primary and the secondary windings which initially has high permeability but relatively low reluctance.

Other objects and advantages will hereinafter appear.

The accompanying drawing illustrates a preferred embodiment of the invention. In the drawing,

Fig. 1 is a top view of the transformer;

Fig. 2 is a side view of the transformer, while

Fig. 3 is illustrative of the wave shape of the primary current and secondary voltage of the transformer.

Referring to Figs. 1 and 2, the transformer has a closed substantially rectangular main magnetic core 10, made preferably of a single sheet of high permeability magnetic material such as silicon sheet or "Permalloy." Mounted on the core 10 is a primary coil 11 adapted to be connected to a source of primary current, and a secondary coil 12. A magnetic shunt core 13 built up of magnetic sheets is mounted on the primary coil 11. The shunt core has a central leg 14 which passes through the center of the coil 11 and two outer legs 15 parallel to the center leg 14 and connected therewith at one end by a yoke 16. Thus the shunt core has the shape of an E and forms an open magnetic circuit of relatively high reluctance for the primary coil 11, which circuit with respect to the primary coil, is in parallel to the magnetic core 10 but is not interlinked

2

with the secondary coil. The cross section of the shunt core is many times that of the core 10, but its reluctance due to the reluctance of its air gap is much higher than the mutual reluctance of core 10.

When an alternating voltage is impressed on the primary coil 11, a flux is induced in the cores 10 and 13. When the current passes through zero the reluctance of the main core 10 is low with respect to that of the shunt core 13. Hence the major part of the initial flux passes through the main core and as the rate of change of the flux is high it induces a voltage of high amplitude in the secondary coil 12. However, the rate of change of current in the primary coil and thus the rate of change of induced flux gradually decreases, while the magnitude of the flux increases. This causes rapid saturation of the main core shortly after the current passes through zero, with the result that the voltage induced in coil 12 falls to a value closely approaching zero. Thus the voltage induced in coil 12 takes a wave form of high peaked amplitude and short duration.

25 Saturation of the main core causes an increased portion of the flux to pass through the shunt core. This increased flux limits the current in the primary coil, thus limiting the energy demand and the heating of the primary coil. Also this shunt reduces the air coupling between the primary and secondary coils and thus minimizes tendency to produce a voltage of sinusoidal wave shape in the secondary coil.

As stated the main core is preferably made of a single loop of flat thin strip material. This assures low eddy current losses therein resulting in a higher peak voltage than would be obtainable otherwise. To further reduce the reluctance of the main core, the abutting ends 40 of the strip are welded together. Instead of employing a single turn for the main core, several strips of magnetic material arranged electrically and mechanically in parallel may be employed.

What we claim as new and desire to secure by Letters Patent is:

1. A transformer comprising primary and secondary coils, a magnetic coupling for said coils affording a magnetic circuit of high permeability restricted in cross section for rapid saturation, and a separate magnetic shunt core mounted on said primary coil at right angles to said magnetic coupling to minimize magnetic leakage and to provide a magnetic circuit in parallel with said magnetic coupling relative to said primary coil, the cross section of the second mentioned

magnetic circuit being large relative to the cross section of the first mentioned magnetic circuit and including an air gap.

2. A transformer comprising primary and secondary coils, a main magnetic core affording a magnetic coupling circuit free from air gaps for said coils, said core comprising a strap of high permeability and of substantially uniform cross section affording rapid saturation resulting in a voltage of high amplitude and short duration being induced in the secondary coil, and a separate magnetic shunt core of relatively large cross section mounted in right angle relation to said main magnetic core to minimize magnetic leakage and affording an open magnetic circuit of relatively high reluctance in parallel with said magnetic coupling relative to said primary coil.

3. A transformer including a main magnetic core comprising a loop of flat thin strip material of high permeability and of substantially uniform cross section affording rapid saturation, primary and secondary coils mounted thereon, said main core affording a magnetic coupling for said coils comprising a magnetic circuit free from

air gaps for inducing in said secondary coil a voltage of high amplitude and short duration, and an E-shaped laminated magnetic shunt core mounted on said primary coil in a plane at a right angle to the plane of said main core and with its center leg passing through said primary coil centrally thereof, said shunt core affording a magnetic circuit in parallel with said magnetic coupling relative to said primary coil, the cross section of said second mentioned magnetic circuit being large relative to the cross section of the first mentioned magnetic circuit and including an air gap.
